(57) **CLAIM**

The ornamental design for a humidity sensor, as shown and described.

DESCRIPTION

FIG. 1 is a front, top and left side perspective view of a humidity sensor showing my new design;

FIG. 2 is a front, top and right side perspective view thereof;

FIG. 3 is a front elevational view thereof;

FIG. 4 is a left side elevational view thereof;

FIG. 5 is a rear elevational view thereof;

FIG. 6 is a right side elevational view thereof; and,

FIG. 7 is a top plan view thereof.
